UNITED STATES PATENT OFFICE.

JOHN SPEIRS, OF JERSEY CITY, NEW JERSEY.

DEVICE FOR CLOSING APERTURES IN VESSELS.

SPECIFICATION forming part of Letters Patent No. 351,132, dated October 19, 1886.

Application filed March 29, 1886. Serial No. 197,062. (No model.)

To all whom it may concern:

Be it known that I, JOHN SPEIRS, of Jersey City, in the county of Hudson and State of New Jersey, have invented a new and Improved Device for Closing Openings in the Hulls of Vessels, of which the following is a full, clear, and exact description.

The object of my invention is to provide a practical device whereby a break or opening 10 in a vessel's hull, caused by collision or other accident at sea, may be practically closed from the inside of the vessel to prevent the inflow of water; and to this end the invention consists of the construction, arrangement, and 15 combination of parts, all as hereinafter described and claimed.

Reference is to be had to the accompanying drawings, forming a part of this specification, in which similar letters of reference indicate 20 corresponding parts in all the figures.

Figure 1 is a broken view of the hull of a vessel, showing the application of my invention. Fig. 2 is an enlarged sectional plan view taken on the line $x-x$ of Fig. 1. Fig. 3 25 is a sectional elevation taken on the line $y-y$ of Fig. 1, and Fig. 4 is a perspective view showing a modification.

A represents the brace-bar provided with the screw B. If the bar is to be used for closing an opening in the side of the hull above the floor C, as at S, Figs. 1 and 2, the bar will be formed at one end with the hook a and at the other with the jaw b to embrace the inner flanges of the angle-irons D D, for holding the 30 bar stationary, so the screw B can be screwed against a plate, E, placed over the opening S to close the same. If the bar is to be used for closing an opening in the bottom of the vessel, as at T, Figs. 1 and 3, it will be provided 35 at one end with the separate hook-bar F and at the other with the angle-piece G, to the upper extremity of which is bolted another angle-piece, H, which, with the horizontal portion g of the bar G, forms a hook to embrace 40 the angle-iron J at the bottom of the vessel, as shown clearly in Fig. 3. The hook F is adapted to embrace the adjacent angle-bar J of the bottom of the hull, as shown also clearly 45 in Fig. 3, so that the pieces F G H, when thus applied, hold firmly the brace-bar A, so that the

screw B may be screwed down upon the plate K, placed over the opening T, and cause it to effectually close the said opening and prevent the inflow of water. The bar G is adapted to be reversed in the brace-bar A, as shown in 55 Fig. 4, to adapt it to be applied to a reverse flange of the angle-iron J, if necessity requires, and the bar F is attached to the bar A preferably by means of a claw, d, made at the end of the bar, so it can be applied to the bar 60 with dispatch and reversed when necessary.

In Fig. 4 the bars F and G are each made in two parts lapped and bolted together, and one part of each bar has a series of holes formed in it, so that by removing the connecting-bolt the bars may be adjusted as to length to 65 suit the depth of space between the bottom of the hull and the angle-irons J.

I am aware that a device for closing apertures in the hulls of vessels has been formed 70 of a tapering plug having a screw secured to its inner end, and a centrally-apertured cross-bar through which the screw loosely passes. The ends of the cross-bar were provided with a hook and a fork, respectively, and three 75 locking-nuts were placed on the screw for adjusting the screw in relation to the cross-piece, and I do not claim the same as of my invention. It will be noticed that my cross-bar is screw-threaded to engage the screw, 80 and that any suitable plate may be clamped over the aperture by the screw. A plug that would fill a shot-hole would not be suitable for a break caused by a collision.

Having thus fully described my invention, 85 what I claim as new, and desire to secure by Letters Patent, is—

1. The device for clamping a plate or covering over an opening in a vessel's hull, consisting of a bar, A, having a central screw-threaded aperture, a separate hook-bar, F, at one end of the bar, the angle-piece G at opposite end of the bar, the angle-piece H, bolted to the horizontal arm of the piece G, and forming in connection therewith a longitudinally-extending hook, and the screw B, passed through the screw-threaded aperture in the bar, substantially as set forth. 95

2. The device for clamping a plate or covering over an opening in a vessel's hull, con- 100

sisting of a bar, A, having a central screw-threaded aperture, the bolt B, passed therethrough, the separate adjustable hook F on one end of the bar, and formed of two overlapped apertured plates, the adjustable two-part angle-plate G, secured to the opposite end of the plate, and the angle-plate H, secured to

the horizontal arm of the plate G, and forming in connection therewith a longitudinally-extending hook, substantially as set forth.

JOHN SPEIRS.
